[57] CLAIM

The ornamental design for a tire, as shown and described.

DESCRIPTION

FIG. 1 is a front elevational view of a tire showing our new design;

FIG. 2 is a perspective view thereof;

FIG. 3 is a side elevational view thereof on a reduced scale the opposite side being a mirror image of that shown; and,

FIG. 4 is an enlarged fragmentary front elevational view thereof.

The tread pattern is understood to be repeated uniformly throughout the circumference of the tire.

FIG. 1

FIG. 2

FIG. 3

FIG. 4
